UNITED STATES PATENT OFFICE.

ALBERT H. HAUSER, OF DEFIANCE, OHIO.

IRONING-TABLE.

949,894.

Specification of Letters Patent. Patented Feb. 22, 1910.

Application filed August 10, 1905. Serial No. 273,617.

To all whom it may concern:

Be it known that I, ALBERT H. HAUSER, a citizen of the United States, residing at Defiance, R. F. D. No. 10, in the county of 5 Defiance, State of Ohio, have invented certain new and useful Improvements in Ironing-Tables; and I do hereby declare the following to be a full, clear, and exact description of the invention, such as will enable others skilled in the art to which it 10 appertains to make and use the same.

This invention relates to ironing tables.

The principal object of the invention is to provide an ironing table with folding 15 legs held in position on the ironing board in a novel manner.

Another object of the invention is to provide, in an ironing table of this character, an arrangement of the legs which will enable 20 an ironing blanket to be readily attached to the ironing board while the same is folded.

With the above and other objects in view, the invention consists, in general, of certain 25 novel features of construction and combinations of parts hereinafter fully described, illustrated in the accompanying drawings, and specifically set forth in the claim.

In the accompanying drawings, like characters of reference indicate like parts in the 30 several views, and:—Figure 1 is a side elevation of a table constructed in accordance with this invention. Fig. 2 is a bottom plan view thereof. Fig. 3 is an enlarged 35 detail section showing the means to hold the table in working position.

The numeral 1 indicates an ironing board provided at one end with the usual reduced portion 2. Adjacent the opposite end a 40 cleat 3 provided with reduced ends 4 extends across the board, the cleat projecting sufficiently beyond the sides of the board to permit a leg to lie between the shoulder at the reduced portion and the board on each 45 side thereof. Pivottally mounted upon the reduced portions 4 of this cleat are a pair of legs 5 and 6. These legs are braced at their lower ends by means of a cross brace 7. Other legs 8 and 9 lie between the legs 5 and 50 50 are spaced apart so that these legs when the board is folded will lie outside of the side edges of the board. The legs 5 and 6 and the legs 8 and 9 are pivotally connected by means of a cross rod or bar 10. The legs 8 and 9 are further provided with a cross 55 brace 11 similar to the cross brace 7 of the

legs 5 and 6. At what may be termed the upper portion of the legs 8 and 9 they are connected by means of a bar 12 which are preferably termed a stop bar. Mounted 60 upon the under side of the board at the reduced end 2 is a longitudinally disposed ratchet bar 13 provided with teeth having their points directed toward the adjacent end of the board. This ratchet bar 13 has 65 a downwardly depending ear 14. The ear 14 is perforated and there is slidably mounted therein what I term a latch bar 19 and this latch bar is provided with a downwardly bent end to form a limit stop 70 for the forward movement of said latch bar.

The legs 5 and 6 extend, when the board is set up, above the board and are connected by means of a shelf 15. There is further provided in connection with this board and 75 pivoted thereto as at 16 a number of rack bars 17 adapted to be swung in or out from the board.

A great advantage to be noted from the peculiar construction of the legs lying outside of the side edges of the board is that when the board is folded the ironing blanket and sheet may be readily applied thereto inasmuch as the legs are all out of the way and do not prevent the blanket and sheet 80 being tacked to the board close to the edge on the under side. Another great advantage of this construction is that the teeth of the rack bar, being pointed toward the end of the board adjacent that bar, permits the 85 ready collapsing or folding of the board when the latch bar 19 is withdrawn from its position underneath the stop bar 12. with the ordinary form of teeth directed in the 90 opposite direction the board must be lifted 95 after the holding means is withdrawn, but in the present instance it is merely necessary to draw the holding means and the legs 8 and 9 immediately collapse themselves.

Having thus described the invention, what 100 is claimed as new, is:—

The combination in an ironing table, of a board, a transversely disposed cleat secured to the under face of said board at one end and having reduced ends projecting beyond 105 the corresponding side edges of the board, a longitudinally disposed ratchet bar secured to the under face of said board at the opposite end thereof and provided with teeth having their points directed toward the adjacent end of the board, a depending ear 110 formed upon the inner end of said bar and

provided with a perforation formed there-through below the lower end of the teeth formed in said bar, a transversely disposed stop bar adapted for interchangeable engagement with said teeth, a longitudinally disposed latch bar movable endwise through said perforation and directly across the edges of said teeth to retain said stop bar between said teeth, said latch bar having 10 its inner end bent downwardly in the rear of said shoulder to provide a stop for limiting the forward movement of said latch bar, a pair of legs pivotally mounted upon the reduced ends of said cleat and extending

above the upper face of said board, a shelf 15 connecting the upper ends of said legs and disposed transversely above said board, and a second pair of legs pivoted intermediate their ends to said first-mentioned legs, said stop bar being secured to the upper ends 20 of said last mentioned legs, all arranged in the manner set forth.

In testimony whereof, I affix my signature, in presence of two witnesses.

ALBERT H. HAUSER.
